AMPOULE-FILLING MACHINE

William T. Barker, Mount Vernon, N. Y.

Application March 18, 1939, Serial No. 262,667

1 Claim. (Cl. 226—19)

This invention relates to the automatic filling of ampoules and the like, and more particularly to a machine for filling ampoules, which are adapted to serve as containers for serums, vaccines, and other medicinal preparations.

One object of this invention is to provide an improved ampoule filling machine of the above nature which will be relatively inexpensive to manufacture, simple in construction, compact, substantially automatic in operation, and very efficient and durable in use.

With these and other objects in view, which will appear as the description proceeds, there has been illustrated in the accompanying drawings, one form in which the invention may be conveniently embodied in practice.

In the drawings:

Fig. 1 is a top plan view of a machine embodying the principles and features of this invention.

Fig. 2 is a longitudinal sectional view through the machine, taken on the line 2—2 of Fig. 1, looking in the direction of the arrows.

Fig. 3 is a broken longitudinal sectional view taken on the line 3—3 of Fig. 1, looking in the direction of the arrows.

Fig. 4 is a transverse cross-sectional view taken on the line 4—4 of Fig. 1.

Fig. 5 is a transverse cross-sectional view, taken on the line 5—5 of Fig. 1, looking in the opposite direction from Fig. 4.

Fig. 6 is a transverse cross-sectional view, taken on the line 6—6 of Fig. 1.

Fig. 7 is an enlarged broken plan view, looking in the direction of the arrows 7—7 in Fig. 2.

Fig. 8 is an enlarged broken vertical sectional view taken generally on the line 8—8 of Fig. 6.

Fig. 9 is a sectional view taken on the line 9—9 of Fig. 8.

Referring now to the drawings wherein like reference characters denote like parts throughout the several views, the numerals 10, 11 and 12 designate three spaced-apart upright frame plates. The intermediate plate 11 is secured to the end plate 10 by tie rods 13 and 14, and to the end plate 12 by a tie rod 15. The plates 10, 11 and 12 are secured together by a tie rod 16 which passes through the plate 11.

In order to feed the ampoules in vertical position through both sides of the machine, provision is made of two parallel vertically spaced-apart helical screws 17 and 18 which extend between and are journaled in the plates 10 and 11. The feed screws 17 and 18 are provided with right and left-hand helical grooves 19 and 20,

respectively. The groove 19 in the upper screw 17, in this instance, is of the proper contour and width to engage the upper small neck portion 21 of the ampoules (see Figs. 10, 11 and 12), while the groove 20 in the lower screw 18 is shaped to engage the lower body portion 22 of said ampoule. The spiral grooves 19 and 20 are of equal pitch, and the screws 17 and 18 are arranged to be rotated in opposite directions so that ampoules directed against the front side of said screws will be fed to the left, as viewed in Figs. 1 and 2, from the plate 11 toward the plate 10, and in so doing, will pass the ampoule filling and sealing stations. The ampoules directed against the rear of the screws 17 and 18 will be likewise fed to the left, and will pass the printing station where suitable indicia will be stamped upon the body portion 22 of the ampoules. The mechanism is so arranged as to cause the ampoules to make one turn for each revolution of the screws 17 and 18.

It will be understood that the filling and sealing devices at the front of the machine or the printing device at the rear may be simultaneously or selectively operated as desired. The ampoules are introduced into the machine by separate guides or chutes 23 and 24, each comprising three metal bars, down which said ampoules slide by gravity toward the feed screws 17 and 18 respectively.

Screw driving mechanism

An electric motor 25 serves as the common source of power for all of the operating parts of the machine, and provision is made of a clutch part 26 rigidly secured upon the end of the motor shaft 27. Another clutch part 28, which is adapted to have frictional engagement with the clutch part 26, is slidably mounted upon a common drive shaft 29 extending through and journaled in the frame plate 12, see Fig. 2. The end 30 of the drive shaft 29 adjacent the frame plate 11 is rotatively supported upon a reduced end 31 of the lower feed screw 18, which is extended through the plate 11 for this purpose. The crank member 32 of a "Geneva" gear is secured upon the end 30 of the shaft 29 to cooperate with the disc 33 of said gear to intermittently drive said feed screw 18. The disc 33 of the "Geneva" gear is rotatively mounted upon a stud shaft 34 extending from the frame plate 11. A gear 35 secured to and rotatable with the disc 33 meshes with a gear pinion 36 secured to the end 31 of the lower feed screw 18, whereby said "Geneva" disc 33 will be intermittently driven.

Another gear 37 is secured on the end 31 of the lower feed screw 18 and meshes with a gear 38 secured on one end 39 of the upper feed screw 17, which is extended through the frame plate 11 for this purpose.

The clutch part 28 is adapted to be slid along the shaft 29 by means of a clutch shifting lever 40 pivoted on a bracket 41 to the frame plate 12 and having a forked end 42 riding in a groove 43 formed in a hub member 44 of the clutch part 28. A hand wheel 45 is provided on the clutch part 28 whereby the shaft 29 may, if desired, be rotated by hand for the purpose of adjusting and timing the various devices driven by said shaft.

In order to transfer the ampoules from the chutes 23 and 24 into the machine, provision is made of a rotary wedge cam 46 secured on the lower feed screw 18 adjacent the frame plate 11, and said cam 46 has curved camming surfaces 47 and 48 (Fig. 7) which serve to drive a pair of parallel slideable ampoule pushers 49 and 50 toward and away from the delivery ends of the chutes 23 and 24, respectively. The pushers 49 and 50 are carried, one at each side of the feed screws 17 and 18, by a cross-block 51 having a longitudinal stem 52 which is slidably mounted in a sleeve 53 secured in and extending from the frame plate 11 over the cam 46. A pin 54 extending downwardly from the stem 52 is alternately acted upon by the camming surfaces 47 and 48 to simultaneously move the pushers 49 and 50 back and forth. The arrangement is such that at every stroke of the pushers 49 and 50, ampoules will be pushed from the delivery ends of both magazine chutes 23 and 24, along which the same are being fed, into the grooves 19 and 20 of the feed screws 17 and 18 to start the feed of the ampoules thereby.

Ampoule filling apparatus

As the ampoules are fed along toward the frame plate 10 by the feed screws 17 and 18, their bases 55 will ride upon a support bar 56, and the body portions 22 of said ampoules are loosely held against the lower screw 18 by a side guide bar 57 (see Figs. 1, 6 and 7). As each ampoule is fed along the support bar 56 to the filling device, it rides onto an elevator plate 58 having a downwardly projecting stem 59 (see Fig. 8) slidably mounted in a stationary sleeve 60. A horizontal pin 61 extending from the stem 59 is connected to one end 62 of a lever 63 pivoted at 64 to the frame plate 11 (see Figs. 3 and 7). The lever 63 is extended along the machine and has a roller 65 mounted upon an offset end 66 thereof (see Fig. 4). The roller 65 is disposed to ride upon the periphery of a cam 67 secured to a sleeve 68, rotatably mounted upon the shaft 29. The rotation of the cam 67 will rock the lever 63 and cause the elevator plate 58 to lift the particular ampoule resting thereon into filling position with respect to a filling needle tube 69 extending downwardly from a liquid measuring device supported upon the tie rod 14 (see Fig. 8). The needle tube 69 is adapted to enter the neck portion 21 of the ampoule for a substantial distance when the ampoule is raised by the elevator 58.

The neck portion 21 of the ampoule is accurately centered with respect to the needle tube 69 entering the same by a funnel-shaped member 70 mounted for free up and down sliding movement on the needle tube 69 and hung from the liquid measuring device by fingers 71 and 72 secured to a square lower casing member 73 of

the measuring device by a nut 74, surrounding said needle tube 69. The lower casing member 73 is secured to a square upper casing member 75 by means of a plurality of cap screws 76 which also clamp the measuring device to the tie rod 14. The screws 76 also clamp the casing members 73 and 75 about a non-corrosive cylindrical sleeve 77, such as stainless steel, located between them. The interior of the cylindrical sleeve 77 is connected by a pipe 79 to an overhead source of liquid supply, such as a reservoir 78 (Fig. 3). The cylinder 77 is connected to the tube 69 by a lower aperture in which the screw 74 is located. It will be understood that the lifting of the ampoule at the filling station takes place during a dwell of the feed screw.

A piston 80, also of non-corrosive material, see Figs. 8 and 9, is slidably mounted in one end of the cylinder 77, the other end of said cylinder being closed by a spring-cushioned non-corrosive hollow plug 81. The adjacent ends of the piston 80 and the plug 81 are spaced apart when separated a determined amount to provide a space 82 having a capacity sufficient to receive the desired amount of liquid from the reservoir 78 when the port 79 is open. The hollow plug 81 is slidably mounted upon a stem 83 and embraces a coiled spring 84, which presses against the stem 83 being seated in a socket 83b therein. The stem 83 is provided with a flange 83a on its inner end. Moreover, as clearly shown in Fig. 8, the interior surface of the hollow piston plug 81 is provided with threads 84a for receiving a hollow threaded screw plug 84b which surrounds the stem 83 and is screwed into the outer end of said hollow plug 81. It will thus be seen that the flange 83a on the stem 83 has an abutting engagement with the inner end of the screw plug 84b to limit the movement of the cushion plug piston 81 with respect to said stem 83. By means of this construction, movement of the piston 80 toward the plug 81 will force the liquid from the cylinder down through the tube 69 into the ampoule, and when the piston 80 strikes the hollow plug 81, the latter will slide upon the stem 83 and protrude out of the cylinder, thus giving a visible indication outside the casing 77 that the filling operation is completed. Simultaneously with the movement of the piston 80 to the left, as viewed in Fig. 8, the hollow plug 81 will be caused to draw away from the piston 80 to open the lower port leading from the space 82 into the needle tube 69.

The piston 80 and the hollow plug 81 are arranged to be moved in the manner above described by cams 85 and 86, respectively, which cams (see Figs. 1 and 2) are secured upon the sleeve 68 to rotate therewith. The cams 85 and 86 have camming grooves 87 and 88, respectively, which serve to reciprocate the piston 80 and hollow plug 81 in timed relation with the rise and fall of the elevator 58 under the action of the cam 67. The cams 67, 85 and 86 are timed to operate the elevator, the piston 80 and the plug 81, as above described, during the period of "dwell" when the screws 17 and 18 are at rest.

The reciprocating piston 80 is connected to one end 89 of a rod 90 (see Figs. 1 and 2), which is connected at its other end to the upper end 91 of a depending lever 92 pivoted at 93 to the tie rod 15 (see Figs. 2 and 4), and extending downwardly therefrom to a point adjacent the periphery of the cam 85. A roller 94 on the lower end of the lever 92 rides in the camming groove 87 of the cam 85 (Fig. 2).

The hollow plug 81 is connected through the

stem 83 to a lever 95 (see Fig. 9), which is pivoted at 96 in a bracket 97 secured on the lower casing member 73. The free end of the lever 95 is connected to a horizontal bar 98 slidably mounted between the casing members 73 and 75 of the measuring apparatus. The other end of the bar 98 is pivotally connected to a rod 100, which in turn is connected at its other end to the upper end 101 of a lever 102. The lever 102 is pivoted at 103 to the tie rod 15 and extends downwardly therefrom to a point adjacent the periphery of the cam 86. A roller 104 on the lower end of the lever 102 rides in the camming groove 88 of the cam 86.

Operation of ampoule filling device

The camming grooves 87 and 88 are of such contour that the piston 80 and hollow plug 81 will be caused to open and close the upper and lower ports of the cylinder 77 at the proper time, and the piston 80 and hollow plug 81 are moved in such a manner that the liquid in the space 82 will be forced downwardly through the needle tube 69 into the ampoule at the proper time. After the liquid in the space 82 has been entirely expelled therefrom, the piston 80 will be retracted slightly, whereby a partial vacuum will be produced in the space 82 for sucking surplus liquid from the upper end 21 of the ampoule 22 to prevent it from wetting the neck of the ampoule which might later cause carbonization when said neck is fused during the sealing operation. Both the piston 80 and the hollow plug 81 will then simultaneously be retracted to the right (see Figs. 8 and 9), the piston 80 preferably traveling somewhat faster than the plug 81 so as to maintain a slight vacuum in the space 82 for causing the liquid from the supply reservoir 78 to be rapidly sucked down into the cylinder when the port 79 is next opened.

Ampoule sealing device

After the ampoule has been filled with liquid as above described, the cam 67 acts to lower the elevator plate 58 to the position shown in Fig. 8. The "Geneva" gear is then partly rotated to cause the feed screws 17 and 18 to force the filled ampoule along the bar support 56 which is inclined upwardly for lifting the ampoule to a raised portion 105 of said bar 56. The ampoule neck portion 21 will at this time be disposed in the path of a plurality of small converging gas jets emitted from a like number of opposed openings 106 and 107 provided respectively in a pair of parallel spaced-apart burner bars 108 and 109 located above the feed screws 17 and 18.

The burner bars 108 and 109 are hollow and supplied with gas under suitable pressure by tubes 112 and 113 (Fig. 6) to a common pipe 114 which is secured to the tie rod 13 by a clamp 115. The supply tube 114 extends from the clamp 115 to a burner regulator 116 and thence to a source of gas supply (not shown) through a tube 117. Manual adjustment of the burner regulator 116 may be readily made to insure the proper blue flames of sufficient heat to melt the top of the neck portions 21 of the ampoules during the dwell period of the spiral screws, whereby perfect seals 118 will be obtained.

Ampoule printing device

The ampoule printing device includes a pair of circular inking ratchet and pawl driven platens 119 and 120 of the usual flat form, said platens being mounted for rotation on a frame member 121 which is secured to the tie rod 16 by screws

122. Inking rollers 123 and 124 mounted to rotate on a common shaft 125 are arranged to be reciprocated over the surface of the platens 119 and 120, respectively, to collect ink therefrom and carry it to printing type 126 and 127 carried by holders 128 and 129 respectively. The holders 128 and 129 are arranged to be swung toward and away from the ampoules being fed by the screws 17 and 18, the bases 55 of said ampoules being slidably supported by an elongated bar 130 (see Fig. 6).

The movement of the inking rollers 123 and 124 over the platens 119 and 120, and of the type holders 128 and 129 toward and away from the ampoules being fed by screws 17 and 18, is effected by an eccentric disc 131 secured upon a sleeve 132 which is rotatably mounted on the common drive shaft 29 adjacent the frame plate 12. The periphery of the disc 131 has a groove 133 in which rides a ring 134. By this construction, it will be seen that the continuous rotation of the disc 131 will reciprocate a connecting rod 135 connected to the ring 134 and cause it to rock an arm 136 secured to a rock-shaft 137 (Fig. 4) journaled in and extending between the frame plates 11 and 12. The rock-shaft 137 extends beyond the frame plate 11, and is also journaled in a bearing plate 138 which extends forwardly from the tie rod 16. A tie rod 139 connects the plate 138 to the frame plate 10.

An arm 140 secured to the rock-shaft 137 (Fig. 6) and extending upwardly therefrom is provided with an elongated slot 141 in its upper end to receive one end of the inking roller shaft 125. An elongated bracket 142 secured to the arm 140 extends under the platens 119 and 120 and then upwardly as an arm 143. The arm 143 has an elongated slot 144 in its upper end to receive the other end of the shaft 125. Springs 145 are connected to each of the arms 140 and 143 and to the adjacent ends of the shaft 125 to retain the respective shaft ends in the slots 141 and 144.

A segment cam 146 (see Fig. 6) having a cam slot 147 therein is secured to the rock-shaft 137, said cam slot embracing a roller 150 carried by a bell-crank lever 148 pivoted at 149 to the bearing plate 138. The other end 151 of the lever 148 is connected by a link 152 to an arm 153 secured to a shaft 154 journaled in a bracket 155 secured on the bearing plate 138. The shaft 154 extends out of the bracket 155 toward the frame plate 10 and has an arm 156 secured thereto (see Fig. 2). The arm 156 has a screw threaded pin 157 therein adjacent its free end 158.

Provision is also made of arms 159 and 160 rotatably mounted on the shaft 154, one on each side of the arm 156. Each of the arms 159 and 160 has an elongated slot 161 therein through which the pin 157 extends. Nuts 162 are screw-threaded on each end of the pin 157 to clamp each of the arms 159 and 160 to the arm 156.

A stud 163 is pivoted on a vertical axis in the upper end of each of the arms 159 and 160, and is clamped in place by a set screw 164 (Fig. 6). Pins 165 are provided in the upper end of each of the studs 163, said pins 165 extending from the studs 163 in opposite directions for receiving lugs 166 extending rearwardly from the type holders 128 and 129 in which the pins 165 are journaled. The lugs 166 are held in place on the pins 165 by set screws 167. The provision of the pin 157 and the elongated slots 161 permits adjustment of the holders 128 and 129 toward and away from the ampoules in respect to the arm 156. The pivoted studs 163 permit twisting of the type holders on

a vertical axis and the pins 165 permit movement of the type holders on a horizontal axis to adjust them relatively to the ampoules being fed along by the feed screws 17 and 18. A rubber covered edge 168 of a stationary bar 169 engages the neck portions 21 of the ampoules as they are fed past the type holders 128 and 129 to cause said ampoules to spin about their vertical axes upon the supporting bar 130.

Operation of the printing device

After the filled and sealed ampoules have been sterilized (by a separate operation outside of the machine), they are fed downwardly through the chute 24, and automatically pushed one at a time by the cam-actuated pusher 50 into the feeding grooves 19 and 20 on the feed screws 17 and 18 respectively. The screws 17 and 18 will then feed the ampoules toward and past the printing type 126 and 127 in the holders 128 and 129 respectively. While the ampoules are being pushed along by the feed screws 17 and 18, the type holders 128 and 129 will be rocked away from printing position at timed intervals to obtain ink for printing the desired indicia on the ampoules. Although two sets of type and type holders are herein shown, only one need be used, or when both are in use, different colored ink may be used on the ink platens to print indicia of two colors on the ampoules.

Selective drive arrangement

Since the ampoule filling and sealing mechanisms need not be in operation when the printing mechanism is in operation, means are herein provided to independently and selectively drive said mechanisms. For this purpose, provision is made of a small cylindrical hub 170 (see Fig. 2) keyed to the common drive shaft 29 and disposed between the sleeves 68 and 132, which are freely rotatable on the shaft 29. A pair of clutch keys 171 and 172, which are freely slideable axially in the cam 85 and in the disc 131 respectively, are adapted to be slid into a key-way 173 formed in the hub 170 by springs 174 and 175 respectively. Clutch control fingers 176 and 177 are arranged to lie in beveled slots 178 and 179 formed in the clutch keys 171 and 172, respectively, to hold the respective keys in retracted position and out of the key-way 173. The clutch control fingers 176 and 177 are urged and retained in key holding position by springs 180 and 181 (see Figs. 1 and 2) secured to a stud 182 extending from the plate 12 and to each finger 176 and 177, respectively.

The clutch control fingers 176 and 177 are adapted to be automatically held out of the slots 178 and 179 respectively to selectively release either of the keys 171 and 172, so long as the ampoules are being fed along by the screws 17 and 18 from the delivery end of either of the chutes 23 and 24. When ampoules are being delivered in front of the screws 17 and 18 from the chute 23 and fed toward the filling device, they are caused to engage a filling detector finger 183 (see Fig. 7) having a stem 184 supported in a stationary bearing sleeve 185 to swing on a vertical axis. The stem 184 extends downwardly and is connected to one end of a hollow shaft 186 (Fig. 7) by means of an arm 187 secured to the lower end of the stem 184, an arm 188 secured on the shaft 186, and a link 189 connecting the arms 187 and 188. One clutch control finger 176 is secured to the other end of the hollow shaft 186.

The other clutch finger 177 is connected to one end of a shaft 190 which extends through the hol-

low shaft 186 and has an arm 191 secured upon its other end. A detector finger 192 similar to the finger 183 is positioned to be engaged by ampoules as they are being fed toward the printing device from the chute 24 and has a stem 193 supported in a stationary bearing sleeve 194 and adapted to swing on a vertical axis depending therefrom. An arm 195 is secured to the lower end of the stem 193 and is connected to the arm 191 by a link 196.

10 Selective operation of filling and printing mechanism

When a plurality of ampoules are being fed from the delivery end of the chute 23 toward the filling and sealing mechanisms, they will automatically engage the detector finger 183 and swing it in a direction to rock the clutch control finger 176 out of the slot 178 in the clutch key 171, whereupon the key 171 will be pressed into the key-way 173 in the hub 170 by the spring 174. The connection between the piston cam 85 and the hub 170 by the key 171 drivingly connects the piston cam 85, the plug cam 86, and the ampoule elevating cam 67 through the sleeve 68 to the common drive shaft 29. This causes the ampoules as they pass the filling device to be automatically filled with liquid and to continue past the sealing device as long as there are any ampoules in engagement with the detector finger 183.

30 When the supply of ampoules in the chute 23 is exhausted, the clutch control finger 176 will be swung into key-withdrawing position by the spring 180, and the above operations will be instantly stopped, thereby preventing the discharge of filling liquid from the needle tube 69.

When a plurality of ampoules are being fed from the delivery end of the chute 24 toward the printing device, said ampoules will engage 40 and swing the printing detector finger 192 in a direction to rock the clutch control finger 177 out of the slot 179 in the clutch key 172. This action causes the key 172 to be pressed into the key-way 173 in the hub 170 by the spring 175, thus drivingly connecting the eccentric disc 131 with the common drive shaft 29, whereupon the printing device will be actuated as above described.

50 When the ampoules are exhausted from the chute 24 and the detector finger 192 is released, the clutch control finger 177 will be urged into key-withdrawing position and the operation of the eccentric disc 131 and printing mechanism will automatically stop.

55 While there has been disclosed in this specification one form in which the invention may be embodied, it is to be understood that this form is shown for the purpose of illustration only, and that the invention is not to be limited to the specific disclosure, but may be embodied in various other forms without departing from its spirit. In short, the invention includes all the modifications and embodiments coming within the scope of the following claim.

65 Having thus fully described the invention, what is claimed as new and for which it is desired to secure Letters Patent is:

70 In an ampoule filling machine, a vertical filling nozzle, means to support an ampoule below said nozzle in alignment therewith, means to deliver a charge of liquid to said nozzle comprising a horizontal cylinder located above said nozzle having a top inlet port connected with a source of liquid supply and a bottom outlet port connected with said nozzle, a hollow cushion pis-

ton having a vertical end face located at one end of said cylinder for initially closing said outlet port, a coiled spring in said hollow piston, a driven slidable stem member having a socket for enclosing the outer end of said spring, a hollow threaded plug screwed into the outer end of said hollow piston surrounding said stem member, a flange on said stem member having abutting engagement with the inner end of said screw plug to limit the outward movement of said piston with respect to said stem, a second piston having a vertical end face located in the other end of

said cylinder for initially closing said inlet port, means to cause said second piston to uncover said inlet port and permit the entrance of the liquid charge into said cylinder, means to cause said cushion piston to thereafter uncover said outlet port, and means to thereafter force said pistons into vertical face to face abutment to expel the liquid charge from said cylinder without injury to said pistons and to insure complete expulsion of said charge from said cylinder into said ampoule.

WILLIAM T. BARKER.
